UNITED STATES PATENT OFFICE.

AUGUSTUS I. BURTON, OF NEW YORK, N. Y.

NECKTIE OR CRAVAT HOLDER.

SPECIFICATION forming part of Letters Patent No. 278,871, dated June 5, 1883.

Application filed February 26, 1883. (No model.)

To all whom it may concern:

Be it known that I, AUGUSTUS IMBRIE BURTON, a citizen of the United States, residing at New York city, county of New York, State of New York, have invented a new and useful Necktie or Cravat Retainer, of which the following is a specification.

My invention is more especially adapted to stand-up collars, to which the following description applies.

The object of my invention is to prevent the vertical or lateral slipping of the band of a scarf or cravat or tie upon the collar, thus holding the neck-wear always in place. For this purpose I have invented a contrivance which grasps the collar and neck-wear independently of each other and in a manner that will appear below.

Referring to the drawings, Figure 1 represents the contrivance as cut out by the die. Fig. 2 shows a side elevation after it has been bent into the shape it is destined to have. Fig. 3 shows it when completed, as seen from behind. Figs. 4, 5, and 6 represent the three stages in the process of fastening it to the collar, and Fig. 7 shows a section on the line Z Y.

In the following description similar letters refer to similar parts.

The contrivance consists, essentially, of two limbs, A and C, a body, B, two prongs, X X, an elevation, E, and an aperture, D.

Referring to Fig. 1, A represents that part which, when the whole is bent up as in Fig. 2, forms one of the limbs. B represents that part which is the body, and D shows the aperture entirely piercing the body B, and standing opposite the elevation E when bent up as in Fig. 2. X X are the prongs cut from the body and bent backward, as shown in Figs. 2 and 3, and C is the part which furnishes the other limb, and the office of which is to act as a pin. The limb A is beveled, as shown at H, Fig. 2.

The manner of using the retainer is as follows: C, which is shaped as a pin, is pushed into the inner lining of the band of the tie from above downward, entering the material above and coming out on the inside a short

distance below. The contrivance is thus fastened to the band very firmly; but there, however, exists a possibility of the pin working out, which I prevent by furnishing the retainer with the two prongs X X. These extend as far back as is shown in Fig. 2, and have a direction backward and upward, so that they offer no obstruction to the entrance of the pin into the fabric, but catch when a movement takes place in the contrary direction. The pin can, however, be withdrawn when the wearer desires, since the prongs are situated at a distance either side of C, as shown in Fig. 3. The material has only to be bent backward when the prongs are freed, and the pin may be easily withdrawn. Two of the retainers are in the above manner fastened to that part of the neck-wear that encircles the neck. The retainers should be so located that when the neck-wear is adjusted to the neck one of them will fall about two inches to one side of the collar-button, and the other a corresponding distance to the other side. The neck-wear, the collar being upon the neck, is next adjusted. The position either of the retainers will now have with regard to the collar is shown in Fig. 4. K represents a cross-section of the collar on a line corresponding to the middle of the retainer. The retainer appears in elevation, and is attached to the inner side of the band, although not shown. With the thumb the retainer is pushed down until the collar slips into the position indicated in Fig. 5. It is then pushed up, the collar slipping into the position shown in Fig. 6. The band of the tie or scarf or cravat is now fastened to the collar through the medium of the retainer, which will not slip upon the collar, because the collar, where grasped, assumes a shape calculated to prevent it.

Fig. 7 is a section on the line Z Y, and shows the manner in which the elevation E, acting in conjunction with the aperture D, operates upon the collar to prevent the lateral slipping of the retainer, and with it the neck-wear.

It is essential that A be considerably shorter than B, and C extend no farther down than the curve which unites A and B. The re-

tainer is to be made of some metal of considerable elasticity.

What I claim is—

As an improved manufacture, a necktie and cravat retainer consisting of the body B, provided with the attaching-prongs X X and the aperture D, the pin C, and the limb A,

having the projection, E, all from a single piece of metal, substantially as shown and described.

AUGUSTUS IMBRIE BURTON.
